United States Patent Office.

WILLIAM H. ABEL, OF GREENVILLE, RHODE ISLAND.

Letters Patent No. 80,697, dated August 4, 1868; antedated July 27, 1868.

IMPROVEMENT IN SLEEVES OF KNITTED GARMENTS.

The Schedule referred to in these Letters Patent and making part of the same.

TO ALL WHOM IT MAY CONCERN:

Be it known that I, WILLIAM H. ABEL, of Greenville, in the county of Providence, and State of Rhode Island, have invented certain new and useful Improvements in the Short Sleeves of Under-Shirts or Vests which are worn by children, lads, or misses, or the short sleeves of any similar garments, of which the following is a full, clear, and exact description, reference being had to the accompanying drawings, making part of this specification, in which—

Figure 1 represents one side of a portion of a child's under-shirt or vest, which has my improvements applied thereto.

Figure 2, the opposite side of the same.

Figures 3, 4, and 5, show detached sleeves in different stages of construction.

This invention and improvement consists in making the short sleeves of knitted under-shirts or vests in tapes or strips, with selvage edges to connect with the selvage edges of the body of the garment and the cuff or border, so that instead of having a bulgy seam where the sleeve and the body of the garment or the cuff are united, the selvage edges may be united, and have the surfaces nearly or quite as smooth and even as the other portions, and so that both the sleeve and the body of the garment will shrink in the same direction equally.

Woven fabrics may be employed in the same way, by having the tapes or strips of which the sleeves are made woven with selvage edges to unite with other selvage edges, and thus avoid a bulgy seam.

This invention also consists in forming gussets of sleeves, which are made of knitted or woven tapes or strips, with selvage edges, by folding over the ends or corners, as clearly shown in figs. 3, 4, and 5, of the drawings, and by securing the same, as described.

In the ordinary knitted sleeves of children's under-shirts or vests, the courses of stitches in such sleeves run in the opposite direction to the courses of stitches in the body of the garment, and when such ordinary knitted sleeves are finished ready for the garment, the connecting ends of such ordinary knitted sleeves present a perfect edge of loops or stitches, which will readily ravel, and when these ordinary knitted sleeves are united with the body of the garment, each of the aforesaid loops or stitches must be connected with the body of the garment at the side or some portion of the arm-hole, by sewing, stitching, or otherwise securing each loop or stitch separately to some portion of the edge of the arm-hole or the connecting place for the sleeve, thus making it a tedious and expensive job to connect such ordinary knitted sleeves with the body of the garment; besides, such ordinary knitted sleeves are liable to wrinkle and pucker and greatly annoy the wearer.

In the ordinary short sleeves of garments made of woven fabrics, a gusset is sometimes set in at the under side; and sometimes the under side of the sleeve is cut on an angle, and a seam sewed at the under side of the sleeve, and such sleeve is connected with the body of the garment by a bulgy seam, which, with one or more of such seams required to make the sleeve, renders such sleeves less comfortable and easy than sleeves which have no bulgy seam, but are smoothly connected.

In carrying out my invention I make the portion A, which forms the short sleeve or sleeves, in tapes or strips of any desired width for the length of the sleeve, and then cut said strips into lengths twice as long as the arm-hole, less the width of the strip. These pieces are then folded over, as shown in fig. 3, one end, a, extending beyond the other end, b, the width of the strip.

This extending end is then folded over on the dotted line c, the corner d brought down to the corner e of the end, b, and the parts sewed together on the line e g, when the sleeve is ready to be sewed or otherwise readily and speedily fastened or joined to the sides of the arm-hole, and by a very smooth seam.

The tapes or strips above described have two selvage edges, one of which is to unite with the selvages at the side of the arm-hole, on the line x, figs. 1 and 2, and the other with the cuff B, on the line f, thus forming a very strong, even, and smooth seam where the sleeve and the garment or the cuff are united, and a sleeve that will always shrink in the same direction with the body of the garment, and in the same proportion, as all the courses of stitches in all the parts run in the same direction.

The two angular portions, *A*, form the gusset of the sleeve, and in a cheaper, smoother, and more simple and durable manner than by any other method I have ever seen; and such a sleeve is always easy and very comfortable to the wearer, as no bulgy seams nor puckering or wrinkling are apparent when the garment is worn or washed, or from any ordinary cause, all as will be readily understood by persons skilled in the art of making knitted or looped garments.

Having fully described my invention, what I claim as new, and desire to secure by Letters Patent, is—

1. Making the short sleeves of under-shirts, vests, and similar garments, of tapes or strips which have selvage edges, and in which the courses of stitches or loops run in the same direction as in the body of the garment, for the purpose and substantially as described.
2. Forming the gusset of such sleeves in the manner and for the purpose substantially as described.

WM. H. ABEL.
